Levi Hoffman

UNITED STATES PATENT OFFICE

ADOLPH COHN, OF NORTH BERGEN, NEW JERSEY

SAFETY-RAZOR BLADE-SHARPENER

Application filed November 5, 1927. Serial No. 231,206.

This invention relates to safety-razor blade sharpeners, and is particularly adapted to sharpen blades of the well-known Gillette type.

The main object of the invention is to provide a device of this character consisting of a blade-holder, a sharpening roller, and means for carrying said roller and simultaneously co-operating with the blade-holder for firmly holding the edge of the blade at the proper angle against the sharpening-roller, thus preventing flexure of the blade and insuring a keen edge after a brief operation of the device.

Another object of the invention is to produce a safety-razor blade-sharpening apparatus, embodying practically three members, simple in construction, effective in practical daily use, inexpensive to manufacture, and lending itself especially to quantity production.

The foregoing and other objects of the invention will be hereinafter described and claimed.

One embodiment of the invention is shown in the accompanying drawing, forming a part of this application, and in which Figure 1 is a top plan view; Fig. 2 is a side elevation thereof; Fig. 3 is a longitudinal section on the line 3—3 of Fig. 1; Fig. 4 is a fragmentary side elevation of one end of the sharpening device and illustrates the manner in which the sharpening roller may be removed when worn out and a new roller substituted; Fig. 5 is a top plan view of a modified form of blade-holder; and Fig. 6 is a sectional view thereof on the line 6—6 of Fig. 5.

Similar characters designate like parts in all the figures of the drawing.

In the embodiment of my invention shown in Figs. 1 to 4, inclusive, the device consists practically of three members, viz., a blade-holder 2, a sharpening-roller 3, and a roller-holder 4. The blade-holder and the roller-holder may be stamped out of sheet metal or any other suitable material. The roller-holder 4 has two arms 5 and 6, one of which has a small hole for the shaft 7 of the roller, and the other a slot 8 for receiving the other end of the shaft of the roller, when the latter is sprung into position. The blade-holder

2 is provided with a plurality of prongs 9—9 for holding the blade, and the said holder is also provided with an elongated opening 10, the outer side of which forms the controlling straight edge ruler 10', and which holds the blade at its very edge at the proper angle against roller 3 after being inserted into the opening 10. The blade-holder is pivoted at 11—11 to the roller-holder and is also provided with a flat spring 12 which bears upwardly against the under side of the roller-holder to hold it apart from the roller to allow space for inserting the edge of the blade in the opening 10. The sharpening-roller 3 is provided with a very thin tape or ribbon 13, impregnated with a hardening abrasive paste to prevent deformation of the tape while the edge of the blade rests upon the roller under pressure during the operation of the device. Any other suitable covering in any other form may be used on the roller as the sharpening, stropping or abrasive means, or the roller may be made of any suitable material without the tape or ribbon or any covering.

When the blade to be sharpened has been placed in proper position for that purpose (see Fig. 1), the blade-holder and the roller-holder are firmly compressed by the fingers of one hand of the user and the roller 3 rotated by the handle 14 by the other hand of the user, the edge of the blade during the operation being held at the proper angle against the sharpening-roller by a sort of leverage action by which the inner point 18 of the slot or opening 10 and the stropping surface of the roller 8 form the pressure points in one direction and the edge 10' the pressure point in the opposite direction. The portion 10' bears downwardly against the edge of the blade, thus preventing flexure of the blade and insuring a keen edge after a few turns of the sharpening-roller. When the covering 13 of the roller becomes worn, should the roller have a covering, the roller may be removed by first lifting the end from the slot 8 in the arm 6 and withdrawing the shaft 7 from the hole in arm 5 of the roller-holder, whereupon a new roller may be substituted and sprung into proper position.

In Figs. 5 and 6, there is shown a modified form of blade-holder adapted to sharpen blades used with the Gem safety razor. In this instance, the reinforced back (not numbered) of this type of blade abuts at the rear edge against the rear stop 15, struck up from the sheet metal and is held against forward movement against the prongs 16, 16 struck up from the metal by engagement 10 with the front edge of the reinforced back, as more clearly shown in Figure 6. The edge of the blade to be sharpened protrudes through the elongated slot or opening 17, which is brought into stropping or sharpening position by the edge 10' adjacent the cutting edge of the blade.

It is, of course, understood that various changes may be made in the general design of my device without departing from the spirit 10 of the invention or the scope of the appended 15 claims.

I claim:

1. A blade sharpening device for safety 25 razor blades or the like comprising two sections formed of metal stampings pivotally mounted at intermediate points, one stamping being formed with side arms formed with bearing portions for mounting a stropping and sharpening roller and bearing portions 30 for the pivotal mounting means, the other stamping having sidewardly extended tongues forming pivots engaging the pivotal bearing portions of said first stamping, said second stamping being extended beyond 35 the pivot cooperating with said first section to form finger compressing members whereby 40 said roller and blade holder may be drawn towards each other and urge the blade edge into proper sharpening position against said roller.

2. A blade sharpening device for safety 45 razor blades or the like comprising two sections formed of metal stampings pivotally mounted at intermediate points, one stamping being formed with side arms formed with bearing portions for mounting a stropping and sharpening roller and bearing portions 50 for the pivotal mounting means, the other stamping having sidewardly extended tongues forming pivots engaging the pivotal bearing portions of said first stamping, said second stamping being extended beyond the 55 pivot cooperating with said first section to form finger compressing members whereby 60 said roller and blade holder may be drawn towards each other and urge the blade edge into proper sharpening position against said roller, and a tongue stamped from said second stamping in the portion extended, said 65 tongue being displaced to provide means for resiliently spacing said sections from each other.

3. A blade sharpening device for safety 70 razor blades or the like comprising two relatively disposed, pivotal sections including

pivotal means intermediate the length thereof, blade holding and sharpening roller mounting means formed on the ends of each of said sections respectively, the opposite ends of said sections being formed with finger 75 engaging portions to compress the blade holding sections and roller towards each other and into sharpening position, said blade holder mounting means comprising a slotted portion, one wall of which serves to engage 80 the blade adjacent the edge thereof.

In testimony whereof, I affix my signature.
ADOLPH COHN.
